AUTOMATIC FLUID CONNECTION FOR
TOGGLE ACTIONS

Arthur O. Gates, Otto H. Pearson, and George Pearson, Salt Lake City, Utah, assignors, by mesne assignments, to Nicholas L. Strike, Salt Lake City, Utah

Application February 24, 1937, Serial No. 127,352

5 Claims. (Cl. 38—40)

Our invention relates to laundry presses and has for its object to provide a new linkage means for connecting the coacting toggle members to enable the movable head to be adjusted to the stationary buck, regardless of the wear of the padding of either buck.

A further object is to provide a means for taking up the slack in the linkage of the movable buck due to wear of the padding on the pressing bucks which means is essentially formed of a hydraulic cylinder connected into the toggle action and which cylinder allows for a predetermined amount of give but, which when this has taken place then becomes a solid column of hydraulic liquid which is non-compressible.

A still further object is to provide a yielding hydraulic cylinder to be used in presses which allows for by-passing of the fluid in a predetermined amount during the bringing together of the press but which automatically stops the flow of fluid when the moving element has traveled a predetermined distance and which then acts as a solid column of liquid with no yielding action.

A still further object is to provide an automatic fluid cylinder for any toggle action to provide means to lengthen or shorten the travel of the toggle whether used in connection with pressing bucks or any other mechanical action where a toggle connection is used to actuate any movable member.

In the drawings

Figure 1 is a partial section of one of our presses showing the yielding cylinder in use in the toggle connection.

Figure 2 is a rear view of the toggle connection and our cylinder in place.

Figure 3 is a partial section of the same press when actuated with the hydraulic cylinder in the non-yielding position for direct column action.

Figure 4 is a diametrical vertical section of the cylinder.

Figure 5 is a diagrammatic view of our cylinder in any toggle action.

Figure 6 is an end view of concentric crank arm used in the press.

Figure 7 is a face view of Figure 6.

In the drawings in which we have shown our device the framework standard in which my enclosed tire pressing machine is mounted and carried is shown as A, the rear side raised into a pivotal support B for the movable pressing buck C. The stationary buck D is mounted on the table E of the framework standard A.

The movable buck C is mounted on the end

of the buck arm 5 and the buck arm 5 is pivotally mounted on the pivot 6. The end of the buck arm which moves the arm and buck is mounted to a clevis 8 by a pin 9 and the clevis is connected to an adjustable threaded shaft or bar 10. Between the bar 10 and the bar 10a we provide our hydraulic cylinder H which will be described hereafter. The lower end of the bar 10a is set in a clevis 11 and an adjustment lock nut 12a is provided for manual adjustment of the toggle connection of which the bar 10, the bar 10a, and the cylinder H, are all portions. The clevis 11 is connected to an actuating crank lever arm 12 onto extended arms 13 thereof. The crank lever arm 12 is T-shaped in elevation and has the main body connected to the medial joint of the toggle by the extended side arms 13 onto which the clevis is mounted. Extending out from and eccentric from the arms 13 on each side of the crank lever arm 12 are the eccentric or crank arms 14 and 15 which are connected onto a pivotally supported H-shaped member 17 which forms the lower portion of our toggle for actuating the pressing buck. The top ends of the member 17 are connected onto the arms 14 and 15 and the bottom end is connected onto a cross support shaft 18. The shaft 18 is mounted in bearings 19 in the frame A. The lower end of the crank lever arm 12 is mounted on a pin 20 which pin is carried through the bifurcated end 23 of the connecting rod 21 of the power cylinder 22. On each outer side of the bifurcated end 23 of the connecting rod 21 on the pin 20, we mount two ball bearing supported rollers 24 which rollers engage on a cam K which is mounted on the shaft 18 and set to the framework by bolts (not shown) passed through a cross plate of the frame A. The front engaging face of the cam K is mounted on a sloping incline so that when the cylinder is filled forcing the piston 40 outward the connecting rod 21 will be forced out and raised over the top of the cam by the rollers 24 engaging the two sides of the cam K actuating the buck arm 5 and engaging the two bucks.

Our hydraulic cylinder H is the main element in our invention and is connected between the shaft 10 and the shaft 10a. The lower end of the cylinder is connected to the shaft 10a, and the top of the cylinder is closed by a cylinder head 26 held in place by bolts 27. The head 26 is bored to allow the shaft 10 to pass down thereto and the bottom end of the shaft is formed with a valve 30 near the end thereof with the rest of the length of the shaft 10 forming the 55

valve stem 31 extending through the central bore 32 of the piston 33 and having the end threaded to receive a nut 34.

The internal bore of the cylinder H is of two diameters that nearest the head 26 being greater than the bore in which the piston 33 is operated. The valve seat 37 and opening 32 of the piston 33 is of greater diameter than the stem 31 and for greater capacity and strength of the piston, we then provide diverging ports 36 through the head of the piston to allow for quick passage of the fluid therethrough.

The nut 34 is set on the stem 31 a distance from the end of the piston to allow for movement of the shaft 10 sufficient distance to open and close the valve seat 37 of the piston when in operation. The step 38 between the larger diametered chamber 39 and the smaller diametered chamber 40 is to act as a seat for a floating washer or plate 41. This washer or plate 41 is perforated by holes 43 and said plate 41 is mounted loosely on the shaft 10 above the valve and is normally held in tensional contact with the step 38 by a spring 42 mounted surrounding the shaft 10 and extending up the shaft to a cross pin 44, said pin holding the spring in tensional relation to the plate and holding the plate normally against the step and the shaft 10 normally lengthened. The spring is the means for normally holding the link extended and the fluid cylinder is the means for allowing it to shorten. In order to allow for this shortening action we provide a bypass port 45 leading from the chamber 39 into a valve chamber 46. The valve chamber 46 carries a ball valve 47 actuated by a plunger 48. The valve seat 49 for controlling the flow of fluid is formed in the end of an insert 50 in which insert the plunger 48 is operated. The end of the valve chamber leads into a port 51 which port leads into the chamber 40. A spring 53 normally holds the plunger and valve in the open position. Thus when the toggle is being operated and the piston is traveling the fluid is forced through the port 51 into the valve chamber 46, through the valve seat 49, and out of the port 54, in the insert 50, and through the by pass 45 into the chamber 39, allowing for compensation of the length of the toggle to adjust for different thickness of padding or of materials being pressed.

In Figure 5 we have shown a diagrammatic view showing the cylinder H in a toggle action with the arms of the toggle shown as 60, and 61, pivotally connected to each other and to an actuating rod 62. The outer ends of the arms may be pivotally connected to any desired stationary object and one movable object.

As a means to actuate the plunger 48 we have shown an adjustable yielding actuating stop S secured to the frame work A by a cross piece 56 and held adjusted by the lock nuts 57 and 58 and having a spring carried in the housing 65 said spring to allow for movement of the stop S

when engaged by the plunger 48 to prevent breakage of the parts of the device.

Having thus described our invention we desire to secure by Letters Patent and claim:

1. In a press of the class described the combination of a movable and stationary element; a toggle mechanism, a power cylinder to actuate the movable element through said toggle; said toggle having an arm composed of two parts, a cylinder fixed to one part, a piston co-acting therewith affixed to the other part, means to conduct fluid freely from one side of said piston to the other; and means acting when the toggle has traveled to a predetermined position to stop the flow of fluid.

2. In a device as claimed in claim 1, a means interposed and acting between the cylinder and piston to return same to their initial relative positions when the pressure is removed.

3. In a press having a movable and a stationary press element, pressure means including a toggle to cause relative pressing engagement of said elements, a lost motion connection interposed in a portion of said pressure means which is in compression when the movable element has been actuated, said lost motion connection including a piston connected to one part, and a cylinder connected to another part of said pressure means, a fluid in said cylinder, conduit means to allow removal of said fluid from said cylinder under said compression, and valve means in said conduit responsive to movement of the toggle to an almost alined position to stop said fluid removal, whereby further lost motion is prevented and further movement of the toggle to alined position brings the elements into pressing engagement.

4. In mechanism as claimed in claim 1, auxiliary conduit means to conduct fluid past said piston, an auxiliary valve means closed by pressure on the toggle and located in said auxiliary conduit means, a resilient means to open said valve when the pressure is removed from the toggle to allow the fluid to return to its initial position by gravity.

5. A pressing machine comprising a head and bed member at least one of which is movable; a movable pressure applying mechanism for actuating said movable member; a hydraulic cylinder mounted in part of a two piece arm of said pressure applying mechanism, a piston carried in said cylinder and connected to the other part of said arm; means to conduct fluid freely from one side of said piston to the other; valve means acting when the pressure applying mechanism has traveled to a predetermined position to stop the flow of fluid; and means acting between said piston and cylinder to lengthen said arm when the movable bed member has been returned to its initial position.
